(57) **CLAIM**

The ornamental design for a tool bit holder as shown and described.

DESCRIPTION

FIG. 1 is a perspective view of an embodiment of a tool bit holder;

FIG. 2 is a side view of an embodiment of the tool bit holder;

FIG. 3 is a perspective view of an embodiment of the tool bit holder;

FIG. 4 is a top-down view of an embodiment of the tool bit holder;

FIG. 5 is a perspective view of an embodiment of the tool bit holder including exemplary tool bits attached thereto;

FIG. 6 is a side view of an embodiment of the tool bit holder including exemplary tool bits attached thereto;

FIG. 7 is a perspective view of an embodiment of the tool bit holder; and,

FIG. 8 is a perspective view of an embodiment of the tool bit holder including an exemplary cover extending therefrom.

The broken line showings of the exemplary tool bits and the exemplary cover are provided for purposes of environment and form no part of the claimed design. The broken line aspects of the tool bit holder form no part of the claimed design.

1 Claim, 8 Drawing Sheets
